INVENTOR.

BY

Alfred J. Reedy

Chappell & Earl
ATTORNEYS

UNITED STATES PATENT OFFICE.

ALFRED J. REEDY, OF BATTLE CREEK, MICHIGAN, ASSIGNOR TO A-B STOVE COMPANY,
OF BATTLE CREEK, MICHIGAN.

STOVE.

Application filed November 11, 1922. Serial No. 600,245.

To all whom it may concern:

Be it known that I, ALFRED J. REEDY, a citizen of the United States, residing at Battle Creek, county of Calhoun, State of Michigan, have invented certain new and useful improvements in Stoves, of which the following is a specification.

This invention relates to improvements in stoves.

10 My improvements are especially designed by me for embodiment in gas and electric stoves and I have illustrated the same in one form in which I have embodied them in gas stoves although my improvements are desirable and readily adapted for use in other types of stoves and ranges.

The main objects of the invention are:

First, to provide an improved stove body in which the wall attaching parts for the 20 front frame are all hidden or on the inside, thereby adding to the appearance of the structure.

Second, to provide an improved stove embodying the parts of my invention which 25 may be quickly and easily assembled.

Third, to provide an improved stove body which may be made of comparatively light material and at the same time is strong and durable and attractive in appearance.

Further objects, and objects relating to structural details, will definitely appear from the detailed description to follow.

I accomplish the objects of my invention by the devices and means described in the 35 following specification. The invention is clearly defined and pointed out in the claims.

A structure which is a preferred embodiment of my invention is clearly illustrated in the accompanying drawing, forming a 40 part of this application, in which:

Fig. I is a front perspective view of a gas stove embodying the features of my invention.

Fig. II is a front elevation of a slightly modified form, the modification being in the arrangement of the doors and hinges, the other parts being identical with those of Fig. I.

Fig. III is an enlarged fragmentary section on a line corresponding to line 3—3 of Figs. I and II.

Fig. IV is an enlarged fragmentary section on a line corresponding to line 4—4 of Figs. I and II.

Fig. V is a vertical detail section on a line corresponding to line 5—5 of Fig. III.

Fig. VI is a detail section on a line corresponding to line 6—6 of Fig. II, showing the arrangement of the hinge.

Fig. VII is a detail section on a line corresponding to line 7—7 of Fig. I.

Fig. VIII is a detail section corresponding to that of Fig. IV illustrating a slight modification in which the nut of the attaching bolt is secured to the frame member 65 instead of the bolt as shown in Fig. IV.

In the drawing similar reference characters refer to similar parts throughout the several views and the sectional views are taken looking in the direction of the little 70 arrows at the ends of the section lines.

Referring to the drawing, the structure illustrated comprises an oven, designated generally by the numeral 1, and an open top, designated generally by the numeral 2. 75 The oven 1 is provided with a front frame comprising a top member 3 and side members 4. These top and side members are of angle cross section and are formed integral- 80 ly or of a single piece, the corners being cut out to permit their being bent up and welded so that a continuous surface is presented at the front, that is, there is no open joint between the parts. This front frame is disposed with its angles facing inwardly and 85 the front arm thereof has a continuous longitudinal corrugation providing a continuous external bead 5 and an internal channel 6. The attaching bolts 7 are secured, preferably with their heads 8 welded, within 90 the channels. However, the structure is quite satisfactory with the nuts 9 thereof welded within the channels as shown in the modification of Fig. III.

The side walls 10 are provided with angled flanges 11 which are disposed in the angles of the frame, these flanges being inwardly offset, providing shoulders 12 engaging the rear edges of the frame,—see Fig. IV. The attaching strips 13 are arranged 100 in the angles of the wall flanges, clamping the same to the frame, the attaching bolts being arranged through both the flanges and the attaching strips. These attaching strips are preferably channel-shaped as illustrated and arranged to face inwardly, their inner flanges or arms 14 providing supports for the oven linings 15.

The top 16 has downturned side flanges 17 which are secured to the upper edges of the walls 10 by the bolts 18, the upper edges of the walls and the flanges having inturned 5 portions 19 through which the bolts 18 are arranged. The top 16 has an inwardly offset attaching flange 20 which is supported by the top clamping strip 21 which is of the same character as the clamping strips for 10 the side walls described.

The top 16 is provided with a downturned flange 17' at its rear edge which overlaps the rear wall 10' and is secured thereto by the bolts 18'.

15 The door 22 in the embodiment shown in Fig. I is provided with hinges 23 secured at the bottom of the front frame, similar hinges 24 supporting the lower door 25 in the embodiment shown in Fig. II.

20 The door 26 of the embodiment shown in Fig. I is also a drop door, its hinges 23 being the same as the hinges for the bottom door.

In the embodiment shown in Fig. II the 25 upper door 27 swings horizontally upon pintles carried by the hinge members 28 disposed through openings 29 provided therefor in the frame members. These details, however, of the doors form no part 30 of my present invention.

The top frame 30 is the same shape as the front frame of the oven. The grids 31 for the open top rest thereon as shown in Fig. VII.

35 Structures embodying the features of my invention are very attractive in appearance as there are no bolt heads exposed and further the structure is economical in its parts and very easily and quickly assembled.

40 I have illustrated and described my improvements in embodiment which I have found very desirable in use.

I have not attempted to illustrate or 45 describe other adaptations and modifications which I contemplate as I believe the disclosure made will enable those skilled in the art to which my invention relates to embody or adapt the same as may be desired.

Having thus described my invention, what 50 I claim as new and desire to secure by Letters Patent, is:

1. In a stove, the combination of a front frame comprising integral top and side members of angle cross section disposed with the 55 angle facing inwardly, the front arm of said frame being provided with a continuous longitudinal corrugation providing a continuous longitudinal external bead and a continuous internal channel, walls having inwardly offset angled attaching flanges disposed in the angles of said frame with their offsets engaging the rear edges thereof, channel-shaped wall supporting strips disposed in the angles of said wall flanges 60 to face rearwardly, and attaching bolts hav-

ing one member thereof welded in said channel of said frame engaging said flanges and clamping strips, and lining secured to the inner arms of said attaching strips.

2. In a stove, the combination of a front 70 frame comprising integral top and side members of angle cross section disposed with the angle facing inwardly, the front arm of said frame being provided with a continuous longitudinal corrugation providing a continuous longitudinal external bead and a continuous internal channel, walls having inwardly offset angled attaching flanges disposed in the angles of said frame with their offsets engaging the rear edges thereof, wall 75 supporting strips disposed in the angles of said wall flanges, and attaching bolts having one member thereof welded in said channel of said frame engaging said flanges and clamping strips.

3. In a stove, the combination of a frame 80 of angle cross section disposed with the angle facing inwardly, the front arm of said frame being provided with a longitudinal corrugation providing a longitudinal external bead and an internal channel, walls disposed in the angles of said frame, channel-shaped wall supporting strips disposed in the angles of said frame to engage said walls to face rearwardly, and attaching bolts having a 85 member thereof welded in said channel of said frame engaging said flanges and clamping channels, and lining secured to the inner arms of said attaching strips.

4. In a stove, the combination of a frame 100 of angle cross section disposed with the angle facing inwardly, the front arm of said frame being provided with a longitudinal corrugation providing a longitudinal external bead and an internal channel, walls disposed in the angles of said frame, wall supporting strips disposed in the angles of said frame to engage said walls, and attaching bolts having a member thereof welded in said channel of said frame engaging said flanges 105 and clamping channels.

5. In a gas stove, the combination of a frame comprising integral top and side members of angle cross section disposed with the angle facing inwardly, the front arm of said frame being provided with a continuous longitudinal corrugation providing a continuous longitudinal external bead and a continuous internal channel, walls having their edges disposed within said 115 frame, wall supporting strips disposed in the angle of said frame to face rearwardly, and attaching members for said strips welded in said channel of said frame.

6. In a gas stove, the combination of a 125 frame of angle cross section disposed with the angle facing inwardly, the one arm of said frame being provided with a longitudinal corrugation providing a longitudinal external bead and an internal channel, walls 130

- having their edges disposed within said frame, wall supporting strips disposed in the angle of said frame to face rearwardly, and attaching bolts for said strips having one member thereof welded in said channel of said frame.
7. In a stove, the combination of a front frame comprising top and side members of angle cross section disposed with the angle facing inwardly, one arm of said frame being provided with a longitudinal corrugation providing a longitudinal external bead and an internal channel, walls disposed with their edges within said frame, and means for attaching said walls to said frame comprising bolts, one member of which is welded in said channel.
8. In a stove, the combination of a frame member of angle cross section disposed with the angle facing inwardly, one arm of said frame being provided with a longitudinal corrugation providing a longitudinal external bead and an internal channel, and wall attaching means comprising bolts, one member of which is welded in said channel.
9. A stove comprising a front frame of angle cross section disposed with the angle facing inwardly, one arm of said frame being provided with a longitudinal corrugation providing a longitudinal external bead and an internal channel, and attaching means for said frame comprising bolts, one member of which is welded in said channel.
10. A stove comprising a front frame of angle cross section disposed with the angle facing inwardly, one arm of said frame being provided with a longitudinal corrugation providing a longitudinal external bead and an internal channel.
11. A stove comprising a frame member of angle cross section disposed with the angle facing inwardly, one arm of said frame member being provided with a longitudinal corrugation providing an external bead and an internal channel, and attaching bolts having their heads welded in said channel.
12. A stove comprising a frame member of angle cross section disposed with the angle facing inwardly, one arm of said frame member being provided with a longitudinal corrugation providing an external bead and an internal channel, and attaching bolts having one member thereof welded in said channel.
13. A stove comprising a frame member of angle cross section disposed with the angle facing inwardly, one arm of said frame member being provided with a longitudinal corrugation providing an external bead and an internal channel, and attaching members welded in said channel.
14. A stove comprising a frame member of angle cross section disposed with the angle facing inwardly, one arm of said frame having a longitudinal raised rib providing an internal channel, and attaching members welded in said channel.
15. A stove body comprising a frame member of angle cross section disposed with the angle facing inwardly, one arm of said frame having a longitudinal raised rib struck up therefrom providing an internal channel, and attaching members disposed in said channel.

In witness whereof, I have hereunto set my hand and seal,

ALFRED J. REEDY. [L. s.]
